CONVERSION OF HYDROCARBON OILS

Jacque C. Morrell, Chicago, Ill., assignor to Universal Oil Products Company, Chicago, Ill., a corporation of Delaware

Application August 31, 1932, Serial No. 631,174

4 Claims. (Cl. 196—48)

This invention particularly refers to an improved process and apparatus for the conversion of relatively light oil while simultaneously subjecting a heavier oil to milder conversion conditions in the same cracking system and further provides for the separation of insufficiently converted intermediate products of the cracking operation into relatively light and relatively heavy fractions, subjecting said light fractions to further conversion together with the light charging stock and subjecting said heavy fractions to further conversion together with the heavy charging stock.

The light oil treated may comprise a gasoline or naphtha for the purpose of improving their antiknock value. The great flexibility of the process resides in supplying heat to the relatively heavy fractions being charged by the relatively highly heated lighter fractions which are more susceptible to heating at high temperatures for relatively long periods without excessive cracking.

A specific embodiment of the present invention may comprise subjecting a hydrocarbon oil to conversion temperature at super-atmospheric pressure in a heating coil, simultaneously subjecting another hydrocarbon oil of higher boiling characteristics to a milder conversion temperature by commingling it with the stream of heated lighter oil from the heating coil, introducing the hot commingled light and heavy oils into an enlarged reaction chamber maintained at super-atmospheric pressure wherein vaporous and residual liquid conversion products quickly separate and wherein the vapors are subjected to continued conversion, withdrawing residual liquid from the reaction chamber to a zone of reduced pressure wherein its controlled further vaporization is effected, assisted, when desired, by the introduction thereto of all or a portion of the vaporous products separately withdrawn from said reaction chamber, subjecting the vapors, including those resulting from conversion and those resulting from said further vaporization of the residue in the reduced pressure vaporizing chamber, to fractionation whereby their insufficiently converted components are condensed as reflux condensate and arbitrarily separated by fractionation into light and heavy fractions, subjecting the lower boiling components of the vapors, which remain uncondensed by fractionation, to condensation and collecting the resulting products, returning the heavy fractions of said reflux condensate to further conversion, together with the heavy charging stock, and returning the light fractions of said reflux

condensate to further conversion in the heating coil together with the light charging stock.

For the sake of convenience, the light and heavy charging stocks will be hereinafter referred to respectively as primary charging stock and secondary charging stock. The secondary or heavy charging stock preferably comprises an oil of relatively high initial boiling point or of wide boiling range such as crude oil or topped crude, gas oil, fuel oil, residual oil or the like, or mixtures thereof, while the primary or light charging stock preferably comprises an oil of lower initial boiling point or narrower boiling range such as light gas oil or other distillate, gasoline, naphtha, kerosene, pressure distillate bottoms or the like, or mixtures thereof.

Vaporization of the residual liquid in the reduced pressure vaporizing chamber is controlled, in part, by the degree of pressure reduction between the reaction chamber and the vaporizing chamber as well as the temperature at which the residual oil is withdrawn from the reaction chamber and introduced into the vaporizing chamber and may be further controlled by the introduction of all or any desired portion of the hot vaporous products from the reaction chamber into the vaporizing chamber. The vapors may be withdrawn from the reaction chamber together with the residual liquid and the commingled materials introduced into the vaporizing chamber or the vapors may be separately withdrawn from the reaction chamber and separately introduced into the vaporizing chamber, in the latter case, entering this zone preferably below the level of residual oil so that intimate contact is established between the vapors and the residual liquid in the vaporizing chamber.

The light or low boiling fractions of the reflux condensate returned to further conversion, together with the primary charging stock, may vary in boiling point characteristics, depending, in part, upon the nature of the primary charging stock as well as upon the operating conditions employed in the process and the desired characteristics of the final light distillate product of the system. This material may, for example, have an initial boiling point of 400 to 437° F., or thereabouts, when the antiknock value of the total lower boiling products is sufficiently high or when it is desired to separately return said lower boiling products to further treatment, as will be later more fully described. However, when some of the heavy ends of the product of motor fuel boiling range are of poor antiknock value they may be included in the light fractions

of the reflux condensate which, in this case, may have an initial boiling point, for example, of 350 to 400° F., or less. The end-boiling point of the light fractions of the reflux condensate may 5 range, for example, from 450 to 650° F.

As a special feature of the invention, a portion of the light distillate product of the system may be returned to further treatment in a heating coil together with the light or primary charging stock 10 and the low boiling fractions of the reflux condensate, in which case the distillate is preferably subjected to conversion conditions which will materially improve its antiknock value without excessively altering its boiling range.

15 The quantity and quality of the primary charging stock and low boiling fractions of the reflux condensate and the conditions to which they are subjected in the heating coil are so controlled that they will contain an adequate supply 20 of heat for transmission to the secondary charging stock and high boiling components of the reflux condensate with which they are commingled to raise the heavy oils to the desired conversion temperature at the pressure maintained 25 in the reaction chamber. In this manner the light oils are themselves converted and also serve as a heat carrying medium comprising the sole source of heat for the heavier oils. By this method of heating the heavy oils 30 and by quickly removing residual liquid conversion products from the reaction chamber, excessive conversion and the consequent formation 35 of substantial quantities of coke and high yields of gas is avoided while the vaporous products from both the light and heavy oils are subjected to continued conversion in the reaction chamber for a predetermined time, which practice is conducive to the production of low boiling distillates of high antiknock value.

40 The accompanying diagrammatic drawing illustrates one specific form of apparatus in which the features of the present invention are incorporated and in which the process of the invention may be practiced.

45 Referring to the drawing, primary or light charging stock may be supplied through line 1 and valve 2 to pump 3 from which it is fed through line 4 and valve 5 to heating coil 6 wherein it is subjected to the desired conversion temperature by means of heat supplied from a furnace 7 of any suitable form. The highly heated oil is discharged from heating element 6 through line 8 and valve 9 into reaction chamber 10. It will be understood that the oil may be preheated 50 in any well known manner, when so desired, prior to its introduction into the heating coil, although preheating means are not shown in the drawing.

55 Simultaneous with the introduction of heated oil from heating element 6 into reaction chamber 10, a secondary charging stock, of higher boiling characteristics than the primary charging stock, is supplied through line 11 and valve 12 to pump 13 from which it may be fed through line 14 and valve 15 into the line 8, commingling 60 therein with the stream of heated oil from heating coil 6, being thereby heated to a milder conversion temperature than that employed in heating coil 6 and passing thence into reaction chamber 10 wherein it is subjected to conversion.

65 When desired, a portion or all of the secondary or heavy charging stock may be diverted from line 14 through line 16 and valve 17 into fractionator 18 wherein it comes into direct contact with the hot vaporous products undergoing fractionation, assisting their fractionation and being 70

thereby preheated. The preheated secondary charging stock collects, together with the high boiling fractions of the reflux condensate formed in fractionator 18 and said heavy fractions of the reflux condensate or heavy reflux condensate and preheated raw oil, as the case may be, is withdrawn from the lower portion of the fractionator through line 19 and valve 20 to pump 21 from which this material is fed through line 22, valve 23 and line 14 into line 8 and thence to reaction chamber 10 together with the stream of heated oil from heating coil 6. The secondary charging stock or secondary charging stock and heavy reflux condensate may, when desired, be preheated in any other well known manner, not illustrated 15 in the drawing, to below conversion temperature, prior to being commingled with the heated oil from heating coil 6.

20 As already mentioned, the quality and quantity of the oil supplied to heating coil 6 and the conversion conditions to which it is subjected in the heating coil is sufficient to heat the secondary charging stock and low boiling components of the reflux condensate from fractionator 10 which are commingled therewith to the desired 25 conversion temperature under the pressure conditions employed in reaction chamber 10, which preferably employs a substantial superatmospheric pressure substantially the same or somewhat lower than that employed at the outlet from 30 heating coil 6.

Although provisions for so doing are not shown in the drawing, the secondary charging stock and heavy reflux condensate may be introduced into reaction chamber 10 separate from the heated oil 35 from heating coil 6, in which case they are commingled with the heated products in the reaction chamber and thereby raised to the desired conversion temperature. Preferably, however, both streams of oils enter the lower portion of the 40 reaction chamber wherein the residual liquid conversion products quickly separate from the lighter vaporous conversion products, the latter being subjected to continued conversion as they pass upward through the reaction chamber while the 45 residual oil is quickly removed from the lower portion of the reaction zone through line 32 and valve 33 to a reduced pressure vaporizing chamber 34. However, the conversion products may, when desired, enter the upper portion of chamber 50 50 by well known means, not shown in the drawing, being subjected to continued conversion as they pass downward through this zone and being withdrawn in commingled state through line 32 and valve 33 to chamber 34. When vaporous and 55 residual liquid conversion products are separated in chamber 10, as first described, the vapors may be withdrawn from the upper portion of the chamber through line 35 or may pass, all or in part, through valve 36 direct to fractionator 18 or may first be diverted, all or in part, from line 35 through line 37 and valve 38 and introduced into chamber 34, preferably entering this zone below the level of residual material maintained therein in order to assist its vaporization and to assist in regulating the degree of vaporization and quality of the residual liquid product of the system.

65 Chamber 34 is preferably operated at substantially reduced pressure relative to that employed in the reaction chamber and by regulating the degree of pressure reduction in this zone the temperature of the products introduced thereto from chamber 10 and the manner of their introduction, further vaporization of the residual oil may be controlled so that a residual liquid product of 70 75

the desired quality may be produced in chamber 34. The residual oil remaining unvaporized in chamber 34, may be withdrawn therefrom to cooling and storage or to any desired further treatment through line 39 and valve 40. Vapors are removed from chamber 34 through line 41 and valve 42 and pass through line 35 to fractionation in fractionator 18, together with any vapors supplied direct to fractionator 18 from chamber 10, 10 as already described.

The insufficiently converted components of the vapors supplied to fractionator 18 are condensed therein as reflux condensate and arbitrarily separated into low boiling and high boiling components. The high boiling components of the reflux condensate are withdrawn from the lower portion of the fractionator and returned to further conversion together with the secondary charging stock, as already described. The low boiling components of the reflux condensate are withdrawn from the upper portion of fractionator 18 through one or a plurality of lines 43 controlled by valves 44 and pass through line 45 to pump 46 from which they are returned through line 47, valve 48 and line 49 to heating coil 6 for further conversion together with the primary charging stock.

Vaporous products of the desired end-boiling point are withdrawn from the upper portion of fractionator 18 through line 50 and valve 51, and are subjected to condensation and cooling in condenser 52 from which the resulting distillate and uncondensable gas passes through line 53 and valve 54 to collection in receiver 55. Uncondensable gas may be released from receiver 55 through line 56 and valve 57. Distillate may be withdrawn from the receiver through line 58 and valve 59.

A portion of the distillate collecting in receiver 55 may, when desired, be withdrawn through line 60 and valve 61 to pump 62 from which it is returned through line 49 and valve 63 to heating coil 6, together with the low boiling components of the reflux condensate and the secondary charging stock to be subjected in this zone, preferably to conversion conditions which will improve the antiknock value of the recycled distillate. By the use of this feature of the invention which permits dilution of the primary charging stock and light fractions of reflux condensate with a portion of the light distillate product of the system, higher conversion temperatures may be employed in heating coil 6 than would otherwise be satisfactory and this high conversion temperature and increased quantity of heated oil from heating coil 6 are often found useful in furnishing the required heat to the secondary charging stock and heavy fractions of the reflux condensate.

The maximum conversion temperature to which the primary or light charging stock and light fractions of the reflux condensate are subjected in the heating coil may range, for example from 925 to 1050° F. with a super-atmospheric pressure measured at the outlet from the heating coil ranging from 100 to 800 pounds, or more, per square inch. A super-atmospheric pressure substantially equalized with that at the outlet from the heating coil or somewhat reduced, may be employed in the reaction chamber and by commingling the secondary charging stock and heavy fractions of the reflux condensate with the heated products from the heating coil, a reduced temperature ranging, for example, from 850 to 950° F., may be obtained in the reaction chamber. The vaporizing chamber is preferably operated 75 at a substantially reduced pressure relative to

that employed in the reaction chamber, said reduced pressure ranging, for example, from 100 pounds, or thereabouts, per square inch, down to substantially atmospheric pressure and substantially this same range of pressures may be employed in the succeeding fractionating, condensing and collecting portions of the system.

As a specific example of the operation of the process of the present invention, the primary charging stock which comprises about two-thirds by volume of the total raw oil charged to the system is a 45° A. P. I. gravity Pennsylvania naphtha which is subjected in the heating coil to a temperature of about 970° F., at a super-atmospheric pressure of about 400 pounds per square inch. 10 The remaining one-third or secondary portion of the total charging stock is a 22° A. P. I. gravity mid-continent fuel oil which, together with high boiling fractions of the reflux condensate, is commingled with the stream of heated oil from the 15 heating coil, prior to its introduction into the reaction chamber. The reaction chamber is maintained at a super-atmospheric pressure of about 400 pounds per square inch and the vaporizing chamber is operated at a reduced super-atmospheric pressure of about 50 pounds per square 20 inch, which is substantially equalized in the succeeding fractionating, condensing and collecting portions of the system. The overhead product from the fractionator, which is condensed as the 25 motor fuel product of the system, has an end-boiling point of about 400° F., and the low boiling fractions of the reflux condensate returned to the heating coil for further conversion, together with the primary charging stock, have a 30 boiling range of approximately 400 to 600° F. The heavier reflux may be returned together with the heavier charging stock and thus minimize the 35 chances of coking the tube if not to prevent coking altogether.

This operation may yield about 72 percent of 40 motor fuel having an antiknock value equivalent to an octane number of approximately 74, the additional products of the system being about 20 per cent of marketable fuel oil and about 600 45 cubic feet of gas, per barrel of total charging stock.

By returning a portion of the distillate to the heating coil, in an operation such as above described, its antiknock value may be materially increased at the expense of a somewhat lower yield 50 of motor fuel and a corresponding increase in the yield of gas.

Other combinations of charging stocks of various types such as gasolines, kerosenes, etc., with 55 heavy oils such as California, Mexican and Venezuelan residues have been cracked with remarkably good yields of gasoline of high antiknock quality and long operating periods.

I claim as my invention:

1. A process for the conversion of hydrocarbon oil which comprises subjecting raw oil charging stock of low boiling characteristics to conversion temperature at super-atmospheric pressure in a heating coil and communicating enlarged reaction chamber, simultaneously subjecting another hydrocarbon oil charging stock of higher boiling characteristics to a milder conversion temperature in the reaction chamber by introducing it into direct contact with the heated oil from 60 the heating coil, quickly removing residual liquid conversion products from the reaction chamber and introducing them into a reduced pressure vaporizing chamber, subjecting vaporous conversion products to continued conversion in the 65 70 75

- reaction chamber, separately withdrawing them therefrom, introducing vapors separately withdrawn from the reaction chamber into direct contact with the unvaporized residual oil in the 5 reduced pressure vaporizing chamber, whereby to assist its further vaporization, subjecting vaporous products resulting from both the cracking operation and said further vaporization of the residue to fractionation, subjecting the light components of the vapors which remain uncondensed by fractionation to condensation, collecting the resulting distillate and gas, separating the heavier components of the vapors which are condensed by fractionation into low boiling and high boiling 10 fractions, returning the low boiling fractions to the heating coil for further conversion and subjecting the high boiling fractions to further conversion, together with said hydrocarbon oil charging stock of higher boiling characteristics.
- 15 2. A process of the character defined in claim 1 wherein a portion of the distillate, resulting from condensation of the vapors remaining uncondensed by fractionation, is subjected to further conversion in the heating coil, together with the low boiling fractions of the vapors condensed by fractionation and the hydrocarbon oil charging 20 stock of low boiling characteristics.
- 25 3. A hydrocarbon oil cracking process which comprises heating a relatively light oil to cracking temperature under pressure while flowing in a restricted stream through a heating zone and thence discharging the same into an enlarged reaction zone, simultaneously subjecting a heavier oil to milder conversion temperature in the reaction zone by commingling the same with the heated oil from the heating zone, separating the commingled oils into vapors and unvaporized oil in the reaction zone, quickly removing unvaporized oil from the reaction zone and introducing the same in a vaporizing zone maintained under lower pressure than the reaction zone,
- 30 subjecting the vapors to continued conversion in the reaction zone, separately withdrawing such further converted vapors from the reaction zone and commingling the same with the flashed vapors evolved in the vaporizing zone, subjecting the commingled vapors to common fractionation and separating therefrom relatively light and heavy reflux condensates, returning the light reflux condensate to the heating zone and supplying the heavier reflux condensate to the reaction zone together with said heavier oil, and finally condensing the fractionated vapors.
- 35 4. A hydrocarbon oil cracking process which comprises heating a relatively light oil containing a substantial quantity of hydrocarbons within the gasoline range to cracking temperature under pressure while flowing in a restricted stream through a heating zone and thence discharging the same into an enlarged reaction zone, simultaneously subjecting a heavier oil to milder conversion temperature in the reaction zone by commingling the same with the heated oil from the heating zone, separating the commingled oils into vapors and unvaporized oil in the reaction zone, quickly removing unvaporized oil from the reaction zone and introducing the same in a vaporizing zone maintained under lower pressure than the reaction zone, subjecting the vapors to continued conversion in the reaction zone, separately withdrawing such further converted vapors from the reaction zone and commingling the same with the flashed vapors evolved in the vaporizing zone, subjecting the commingled vapors to common fractionation and separating therefrom relatively light and heavy reflux condensate, returning the light reflux condensate to the heating zone and supplying the heavy reflux condensate to the reaction zone together with said heavier oil, and finally condensing the fractionated vapors.
